AIRPLANE CONTROL

William F. Kerlin, Rockfield, Ind.

Application March 8, 1939, Serial No. 260,540

2 Claims. (Cl. 244—83)

This invention relates to airplane controls, and has for the primary object the provision of a device of this character which will permit the pilot to safely handle the airplane while ascending and descending and also while in flight, the ailerons and elevators of the airplane being controlled by the hands of the pilot while the rudder is controlled by the feet.

Another object of this invention is the provision of companion control sticks so mounted and connected with the ailerons and elevators, the pilot may easily control the right and left ailerons independently by movement of the sticks laterally or sideways with respect to a neutral position and one of the sticks is connected to the elevators so that they may be moved in opposite directions by a forward and backward movement of the stick to which they are connected, the other stick being free to move therewith without either stick operating or moving the ailerons from a selected position.

A further object of this invention is the provision of means for automatically returning the sticks to neutral position when freed and acting to retain said sticks against movement relative to each other until manually moved or operated.

With these and other objects in view, the invention consists in certain novel features of construction, combination and arrangement of parts to be hereinafter more fully described and claimed.

For a complete understanding of my invention, reference is to be had to the following description and accompanying drawings, in which:

35 Figure 1 is a top plan view illustrating an airplane equipped with a control for the ailerons, elevators and rudder thereof and constructed in accordance with the present invention.

Figure 2 is a fragmentary perspective view illustrating the control sticks and the mounting therefor.

Figure 3 is a side elevation, partly in section, illustrating the control sticks and a part of the mounting.

45 Figure 4 is a sectional view taken on the line 4—4 of Figure 3.

Figure 5 is a rear elevation partly in section illustrating the control sticks and the means of returning said sticks to neutral position.

50 Figure 6 is a sectional view taken on the line 6—6 of Figure 5.

Figure 7 is an end view illustrating one of the control sticks.

55 Figure 8 is a detail sectional view taken on the line 8—8 of Figure 6.

Figure 9 is a plan view illustrating the control for the rudder.

Figure 10 is a detail sectional view taken on the line 10—10 of Figure 9.

Figure 11 is a plan view illustrating a bracket 5 for support of cables or flexible elements employed for connecting the control sticks to the ailerons and elevators.

Figure 12 is an edge view illustrating the bracket.

Referring in detail to the drawings, the numeral 5 indicates in entirety an airplane of a conventional construction wherein the fuselage is indicated by the character 6, the wings by the character 7. The wings are equipped with ailerons 8. The fuselage 5 has the usual cockpit 9 and the tail construction is indicated in entirety by the character 10 including the elevators 11 and rudder 12. The parts briefly described are common in airplane construction and are merely shown and briefly described for the purpose of outlining the present invention.

Mounted in the cockpit 9 is a control stick mounting 13 of a gimbal ring type consisting of an annular member 14 having thereon oppositely disposed pintles 15 adapted to be journaled in suitable anti-frictional bearings 16 carried by the fuselage 6. The annular member 14 has a supporting shaft 17 mounted thereon and arranged at right angles to the pintles 15 and provides a journal mounting for companion control sticks indicated by the characters 18 and 19 which extend above and below the mounting and have secured to their lower ends counter-balance weights 20 and their upper ends provided with hand grips 21. The mounting 13 permits the control sticks to be manually moved forward and backward due to the pintles 15 rotating in the bearings on journals therefor. Also the control sticks may be moved sideways without interference with each other due to their rotatable mounting on the shaft 17.

The counter-balance weights are of hollow construction and have openings 22 so that the amount of ballast within the weights may be varied. The purpose of the weights is to maintain the control sticks 18 and 19 in vertical position and to return said sticks to this position when freed. Mounted on the weights are magnets 22 acting to attract the weights and thereby maintain the sticks against relative movement with respect to each other until manually operated. The weights also are equipped with magnets 23 which when moved in the vicinity of a ring 14' adjacent mounting 13 will tend to sup-

- port the sticks in their lateral position relieving the operator of some of the load caused by the counter-balance weights when the sticks are in the latter-named position. The weights when 5 moved a certain distance away from the ring 14 will of course destroy the attraction between the ring and the magnets and the sticks may freely move to vertical position by the weights when manually freed.
- 10 Flexible elements 24 are connected to the control stick 19 above and below the mounting 13 and cross each other and are connected to the ailerons 8 on the left wing of the airplane. Flexible elements 25 are connected to the control 15 stick 18 above and below the mounting 13 and are crossed with each other and connected to the ailerons 8 of the right wing of the airplane.
- This it will be seen that the ailerons may be independently controlled with respect to each 20 other by the manipulation of the control sticks laterally or sideways with respect to a neutral position.

Flexible elements 26 are connected to the control stick 18 above and below the mounting 13 25 and extend rearwardly and are connected to the elevators 11 whereby movement of the control stick 18 forwardly and rearwardly with respect to the neutral position will operate the elevators in opposite directions. To guide the flexible elements, brackets 27 are mounted on the fuselage and are equipped with rollers 28 to receive said 30 flexible elements. The brackets and the rollers properly guide the movement of the flexible elements and prevent them from dragging and contacting with the fuselage or any other parts of 35 the airplane.

Mounted on the floorboards of the cockpit 9 are pivotally mounted pedals 29 provided with arcuately curved members 30 which extend through 40 openings provided in the floorboards and have mounted thereon coil springs 31 bearing against the pedals 29 and the floorboards acting to restore the pedals 29 to a neutral position. Flexible elements 32 connect the pedals to the rudder 45 12 so that the pilot by employing his feet may move the rudder in opposite directions by depressing first one pedal and then the other pedal, the springs acting each time to restore the pedals to neutral position. For instance, if the rudder 50 12 is to be moved to the left, the left pedal is depressed while the right pedal may swing rear-

wardly to permit the rudder to turn to the left. The same operation occurs when the right pedal is depressed, the left pedal swings rearwardly allowing the rudder to turn to the right.

From the foregoing description taken in connection with the accompanying drawings, it will be seen that the companion control sticks permit the pilot to have complete control over the right and left ailerons of the wings 7 and also to operate the elevators by moving one of the sticks 10 forwardly and rearwardly, the other stick being free to follow the movement of its companion stick.

It is believed that the foregoing description, when taken in connection with the drawings will 15 fully set forth the construction and advantages of my invention to those skilled in the art to which such a device relates, so that further detailed description will not be required.

Having thus described by invention, what I 20 claim is:

1. An airplane control device comprising an annular member mounted for pivotal movement in opposite directions from a normal horizontal position, a shaft having opposite ends secured 25 to said annular member and arranged at right angles to the pivot of said annular member, control sticks journaled on said shaft and extending above and below the annular member, means for connecting said sticks to control devices of an 30 airplane, weights on the lower ends of the sticks normally sustaining the sticks vertically, and magnetic means on said weights to releasably restrain the sticks in parallelism.

2. An airplane control device comprising an 35 annular member mounted for pivotal movement in opposite directions from a normal horizontal position, a shaft having opposite ends secured to said annular member and arranged at right angles to the pivot of said annular member, control sticks journaled on said shaft and extending above and below the annular member, means for connecting said sticks to control devices of an 40 airplane, weights on the lower ends of the sticks normally sustaining the sticks vertically, magnetic means on said weights to releasably restrain 45 the sticks in parallelism, and magnetic means on the weights to coact with the annular member in releasably restraining the sticks swung laterally of the normal vertical positions of said sticks. 50

WILLIAM F. KERLIN.
